UNITED STATES PATENT OFFICE.

WILLIAM C. BAXTER, OF EAST BRIDGEWATER, MASSACHUSETTS, ASSIGNOR
TO UNITED STATES AUTOMATIC BOX MACHINERY COMPANY, OF BRIDGE-
WATER, MASSACHUSETTS, A CORPORATION OF MAINE.

PAPER-BOX MACHINE.

SPECIFICATION forming part of Letters Patent No. 737,819, dated September 1, 1903.

Application filed July 12, 1902. Serial No. 115,305. (No model.)

To all whom it may concern:

Be it known that I, WILLIAM C. BAXTER, a citizen of the United States, residing at East Bridgewater, in the county of Plymouth and State of Massachusetts, have invented an Improvement in Paper-Box Machines, of which the following description, in connection with the accompanying drawings, is a specification, like characters on the drawings representing like parts.

This invention relates to machines for making boxes from cardboard, pasteboard, or other suitable blanks, of the general type of apparatus shown in United States Patent No. 519,531, dated May 8, 1894, and later patents, No. 546,318, September 17, 1898, and No. 681,652, dated August 27, 1901. Such later patents were for improvements on, additions to, or variations of certain features or mechanisms embodied in the earlier patent; and my present invention, relating to this same type of machine, provides for further improvements therein which have become necessary in order to enable the parent machine to handle work of a greater range and to insure increased accuracy in operation.

One object of my present invention is to provide for the positioning of the blank with the greatest accuracy in readiness for the action of the former and other coöperating devices which fold or bend the parts of the blank to make the completed box.

Another object of the invention is the provision of means for accurately and readily handling the blanks from which long or deep boxes are to be made, such blanks by their peculiar shape having presented new problems to be solved in the mechanism for handling the same.

Another object is the production of means for overcoming the effect of the suction between adjacent blanks when the topmost blank of the pile is engaged by the gummer-picker and lifted preparatory to the feeding of the blank to the forming mechanism.

Frequently two or more blanks will be lifted, owing to the suction action between them, and I have provided novel separating means to separate the second blank from the topmost

blank of the pile of blanks when the latter is lifted by the gummer-picker.

Another object of my invention provides novel and effective means for shedding the completed box from the former.

These and other novel features of my invention will be fully described hereinafter and particularly pointed out in the following claims.

The general organization of the machine is substantially the same as shown in the patents hereinbefore referred to, and in the following specification only so much of the old mechanism will be referred to as may be necessary to a proper understanding of the novel features of my present invention.

Figure 1 is a left-hand end elevation of the machine shown in Fig. 2, the mechanism for operating the side and end followers being omitted in order to more clearly illustrate the novel features of my invention. Fig. 2 is a side elevation of the apparatus, the pile of blanks being shown at the right-hand end thereof. Fig. 2^a is an enlarged perspective detail of a part of the blank-feeding means. Fig. 2^b is an enlarged detail of a part of the mechanism shown in Fig. 2 for effecting the accurate positioning of the blank beneath the former. Fig. 2^c is an enlarged perspective view of a part of the shedding means. Fig. 3 is a partial top or plan view, enlarged, of the mechanism shown in Figs. 1 and 2, but with the arches or frames for sustaining the former and gummer-picker and such parts omitted, the blank being shown as just about to be positioned beneath the "former." Fig. 4 is an enlarged side elevation of the mechanism shown in plan in Fig. 3 viewing the latter from the side nearest the spectator. Fig. 5 is an enlarged longitudinal vertical sectional view taken through the former and former-shaft to show clearly the novel shedding means. Fig. 6 is an enlarged detail, in side elevation, showing the positioned blank resting on the followers and the former on its downward stroke, just touching the blank, the nearer side follower being omitted. Fig. 7 is a similar view, but showing the former as having continued its movement far enough

to begin the formation of the box in full lines, the subsequent position of the parts being shown in dotted lines. Fig. 8 is an enlarged view of the controlling-cams for governing the operation of the various mechanisms which act upon the blank. Fig. 9 is a perspective view of the blank flattened out, showing the gummed surface and the general shape or configuration of the blank to be handled by the various mechanisms embodying my invention. Fig. 10 is a similar view, but showing the blank after a partial bending or forming has been effected.

It may be stated here that the formation of comparatively large boxes having a very considerable depth relative to their cross-sectional area has given rise to some grave difficulties in practice, necessitating the construction of means for overcoming the same, and my present invention in certain of its features deals more particularly therewith, while other features of the invention have a broad or general application to machines for making paper boxes, as will more fully appear hereinafter.

Referring to Figs. 9 and 10, b^x represents the bottom, oblong in shape; b' the opposite long sides, the former having the longitudinal stay-sections $b^2 b^2$, over which the end sections b^3 , which have gum applied thereto by the gummer-pickers, are folded and cemented by the gum, the gummed surface being shown by the shaded parts b^{xx} . The bottom b^x has at its opposite ends the bottom-stays b^4 , which are upturned and stuck to the gummed end sections b^3 , and the side b' is longitudinally slotted at 2 2 to form a top or cover flap b^5 , while the opposite side b' has a prolongation b^6 between and beyond the stay-sections b^2 to constitute the coöperating cover-flap. When the box is completed, the end sections b^3 are bent over or folded on the dotted lines 2 3 to complete the cover or top of the box, and when the latter is completed the stay-section b^2 and adjacent bottom-stay b^4 will be in the same plane and stuck to the outer end section b^3 by the gummed portion b^{xx} thereof.

In Figs. 2, 3, and 4 the pile of blanks B^x is shown as piled on an automatic elevator of any suitable construction common in envelop and box machines, over which pile moves the gummer-picker, comprising a vertically-reciprocating shaft f , to which are attached the depending gummer members g' , supplied with gum at the proper time by a gum-supplying roll g , Fig. 2, mounted to slide horizontally on supports g^x and operated by suitable mechanism forming no part of my invention. The gumming-faces of the members g' are of the shape of the surface to be gummed, and herein such shape corresponds to the shaded portions b^{xx} in Fig. 9, there being two gummer members in the present instance. The reciprocation of the shaft f is effected by the rocker-arm f^4 on the usual rock-shaft f^5 , to which latter rocking motion

is periodically imparted substantially in a manner well known in machines of this type; but to give some yield to the gummer-picker in its descent I have provided the rocker-arm f' with a lateral pin f^2 to enter a slot f^3 in the link f^6 of the actuating mechanism, a spring s , attached at one end to the arm f' , being secured at its other end to the link and normally acting to retain the pin f^2 in the bottom of the slot. If for any reason the gummer-picker cannot descend the normal distance, the link f^6 can complete its stroke, the spring stretching while the pin f^2 travels in the slot f^3 , and a smash of the parts is obviated. When the gummer members g' descend upon and gum the topmost blank of the pile, the said blank is lifted by the ascent of the gummer-picker, and sometimes the suction between the blanks will cause two or more blanks to adhere and be lifted with the topmost blank, so that the operation of the machine is interfered with and annoying stoppage and delay ensue. In order to prevent such accidents, I have provided means to effectually separate the second blank of the pile from the topmost blank when the latter is lifted, and to this end I have mounted on the frame two upright posts t^4 , longitudinally notched at t^5 , Fig. 3, to receive the leading corners of the blank-pile and act as positioning-gages therefor. A cross-bar t^1 is secured to the gages, and blocks t^2 are fastened to the cross-bar in such a position as will enable the flat faces of thin blade-like separators t^3 to engage edges of the blanks, said separators being attached to the blocks. Herein I have so located the latter that the blades enter the slits 2 2 of the blanks. Now when the topmost blank is lifted by the gummer-picker the adhesive action of the gum will be greater than the frictional action between the separators t^3 and the contacting edges of said blank; but such frictional action between the next blank below and the separators is great enough to overcome any adherence between the top and second blanks due to suction or otherwise, and only the topmost blank will be lifted from the pile by itself.

Any suitable means may be employed to strip the gummed blank from the members g' at the proper time, and as such stripping devices are common in envelop and paper-box machines, types thereof being shown in the patents referred to hereinbefore, I do not herein show or describe such devices in detail, it sufficing to say that the bars u , Fig. 2, are similar to those shown in Patent No. 546,318 and operate, as therein described, to strip the blank from the gummer-picker at the proper time.

The box-forming mechanism is generically such as is shown in the patents hereinbefore referred to, and comprises a former F , attached to a vertically-reciprocated hollow plunger or shaft F' , mounted in the arch-frame Q , and a folding box or throat constituted by the end followers $B B$ and the vertical or upstanding

side-folding plates D D, adjustably arranged in opposite pairs on the slides E, which extend across the bed-plate Q^X of the main frame and are reciprocated by or through the rock-
5 ing of the rock-shafts 47, having arms 48, pivotally connected with links 49, the lower ends of the latter coöperating with and being actuated by suitable cams, all substantially as in Patent No. 519,531. When the former F
10 has descended part way, the movable parts B B and D D have their closing movements, the latter acting upon the long opposite sides b b' of the blank, while the end followers operate to press the gummed end sections b³
15 upon the corner or stay sections b² in well-known manner. The toggle mechanism for moving the end followers B B is not shown herein for the sake of clearness, and it is in practice substantially as shown in Patent No.
20 519,531.

In Figs. 3, 4, and 6 the throat members are shown in the position assumed as the former F is descending, the said members standing at the boundaries of a rectangle somewhat
25 larger than the box-bottom b^X, Figs. 9 and 10. The horizontal conveyer-rod^s h h are supported by and longitudinally movable in guides in the followers B in well-known manner, having at their forward ends the abutments or
30 abutment-hooks h⁷, adjustably secured to the rods, substantially as in Patent No. 681,652, to engage the lateral edges of the blank lifted from the pile by the gummer-picker and under which the conveyer-rod^s are thrust, the
35 opposite or feeding stroke of the latter acting to place the blank or blank-supporting means, to be described, over the folding-throat. A cross-bar h^X, mounted to slide on a stand M at the left-hand end of the machine, Fig. 2, is reciprocated by the swinging arms h' on a rock-shaft h², the latter being rocked in usual manner, and the cross-rod is adjustably connected with the conveyer-rod^s h by extending between a pair of annularly-grooved rolls
40 h³, (see Fig. 2^a), rotatably mounted on a collar h⁴, secured by a set-screw 80 to the rod h, one on each. Inasmuch as the end followers B B (in which said rods slide) are movable toward and from each other, it is necessary
45 to provide for corresponding movement of the rods relative to the cross-bar h^X, and this is effected by the rolls h³, which permit free lateral movement of the rods and greatly reduce the friction on the cross-bar, the grooving of
50 the rolls preventing disengagement of the rods and cross-bar.

The plates D in Patent No. 681,652 are provided at their upper outer corners with lips of a peculiar shape to coöperate with the
60 other parts of the box-forming mechanism in folding the blank, and in my present invention I make use of similar devices, but modified to adapt them to the somewhat peculiar character of the work to be performed.

65 Referring to Fig. 9, it will be seen that the end sections b³ project laterally beyond the bottom-stays b⁴, and in forming the box it is

necessary to bend up the said stays before the end sections b³ are bent in order that the latter may assume their proper position outside of the bottom-stays. To this end the side plates D at the end of the machine nearer the blank-pile B^X are provided each with a lip m at the upper outer corner thereof, the lips being so located and of such length that they will project beneath the bottom-stays b⁴ and the adjacent ends of the stay-sections b² when the blank is in proper position to be folded, while the opposite pair of side plates D have at their outer upper corners projecting short lips m', laterally offset from the lips m, (see Fig. 3,) the lips m' extending beneath the end sections b³ of the blank, but not being long enough to engage the bottom-stays, it being remembered that in Fig. 3 the blank is shown as slightly beyond its final position relatively to the box-forming mechanism.

The position of the lips m and m' when the box is being formed is shown in Figs. 6 and 7, and as the points of the lips then overlap the object of laterally offsetting them, as shown in Fig. 3, will be apparent, and by reference to said figure it will also be seen that the lips m are nearer the longitudinal lines 95 on which the stay-sections b² and bottom-stays b⁴ are to be folded. This results in turning up the parts b² and b⁴ of the blank before the lips m' act to turn up the end sections b³, so that the latter will be outside, when the former F descends into the throat.

It has been found necessary in making boxes of such depth as herein illustrated to support and lift not only the long sides b and b', but also to provide for lifting the end sections b³ in unison with the side b', for in using light-weight stock the sides will bend back if not thus lifted at the time the former descends into the throat, and, furthermore, the end sections b³ of the blank tend to bend down or sag out of the plane of the side b', so that the forming mechanism will not operate properly to make a perfect box. In order to support and lift the side b', I have provided an elongated lifter m² concaved in the direction of its length, and pivoted at or near its inner end on a pin m³, mounted on the left-hand pair of side-folders D D, Fig. 3, to swing between them, the end of the lifter being extended and down-curved at m⁴ to constitute an operating-cam. At its outer end the lifter is laterally extended, as at m⁵, Fig. 3, to form a larger support for the side b' of the blank, the cam m⁴ projecting into the throat in the path of the former F, Fig. 6, as folding is about to begin. The former as it descends engages the bottom b^X of the blank and presses it downward into the throat, the side-folders and end followers then being in the position shown in Fig. 6, and as the former continues its descent the bottom of the box being formed wipes over the cam m⁴ and swings the lifter up from the position shown in Fig. 6 to upright position,

(see dotted lines, Fig. 7,) with the side b' against the corresponding vertical face of the former F. At this time the cam m^4 is moved into dotted-line position out of the path of 5 the descending former as it carries the partly-folded blank down into the throat to complete the folding.

The means for supporting and lifting the end sections b^3 and the side b of the blank are 10 mounted on the end followers and will now be described.

Brackets N on the bed Q $\times$ of the frame of the machine, Figs. 3 and 4, support a rock-shaft N $\times$, which is extended transversely of 15 and through holes in the end followers B B, and outside of the followers short upturned arms n are secured to the rock-shaft, the upper ends of the arms having holes to loosely receive inwardly-extended pins n', fast on 20 lugs n ^{2} , adjustably held by set-screws n $\times$ in sockets n ^{3} , secured to or forming part of stands N', attached to the slide E nearer the blank-pile outside the followers B. The latter have a movement toward each other longitudinally of the rock-shaft N $\times$, and, remembering that the slide E moves toward and from the former F, it will be manifest that movement of the slide to the left, Figs. 3 and 25 4, will act through the pins n' and arms n to rock the shaft N $\times$ in the direction of arrow 90, Figs. 6 and 7. Hubs n ^{4} are secured to the rock-shaft between the followers, (see Fig. 3,) and to each hub a long rod or finger n ^{5} is secured, the fingers being located in parallelism 30 below the side b of the blank when the latter is in position over the folding-throat, and when the rock-shaft is turned, as has been described, the fingers will rise, (see Fig. 7,) lifting the side b of the blank, as shown, such 35 lifting being simultaneous with the inward or closing movement of the side-folders D D. I have provided fingers n ^{6} for supporting and lifting the end sections b ^{3} of the blank, said fingers being secured to hubs n ^{7} , fulcrumed 40 outside of the end followers on lateral pins n ^{8} , attached thereto, each hub having a depending offset arm n ^{9} to receive loosely in its lower end a stud n ^{10} , inturned from a shank n ^{12} , secured adjustably in the adjacent end 45 50 of the stand N' by a set-screw n ^{13} . The movement of the stands N' which operates to rock the rock-shaft N $\times$ also operates through the devices described to rock the hubs n ^{7} and swing the fingers n ^{6} from the position shown 55 in Fig. 6 to that shown in Fig. 7, the lifting movement of the fingers n ^{5} and n ^{6} being timed to act in unison with the lifting movement of the side-lifter m ^{2} , hereinbefore described.

In Fig. 7 the extreme upward movement of 60 the two pairs of fingers is shown, the parts of the blank at opposite sides of the bottom section b $\times$ thereof being thereby started; but as the side b' with its attached end sections b ^{3} is much the heavier the lifter m ^{2} will continue 65 to support and raise that side as the former F descends. The inner faces of the lips m and m' are beveled or inclined, as shown in

Fig. 3, to effect the bending of the parts b ^{2} and b' of the blank by the lips m, and a like office is performed by the lips m' for the parts b ^{3} , as will be manifest to those familiar with machines of this class, as the former F moves downward. Supposing now that the blank is accurately positioned relatively to the box-forming mechanism and that the former is 75 moving downward with the parts in the position shown in Fig. 6, the pressure of the former upon the blank will cause the sides b and b' to rise, the tops of the plates D D acting as fulcra, and the lips m begin to turn up 80 the stay-sections b ^{2} and bottom stays b ^{4} , while the lips m' perform a like office for the gummed end sections b ^{3} . Now, however, the opposite pairs of plates D D approach the former while the latter descends and the lips m and m' move toward each other, while simultaneously 85 with such movement the fingers n ^{5} and n ^{6} are swung upward, carrying the superposed parts of the blank into about the position shown in Fig. 7, in which the plates D D have completed their inward movement, it being remembered that the side lifter m ^{2} is actuated by the descending former, as described. The folding-up action is continued and completed 90 by the descending former, the lips m' folding 95 over the end sections b ^{3} outside of the bottom and stay sections b ^{4} b ^{2} , the continued movement of the side lifter m ^{2} to its dotted-line position, Fig. 7, aiding the lips m' in folding over the end sections b ^{3} , the gummed surfaces thereof coming in contact with the bottom and stay sections. The latter are turned 100 angularly against the sides of the former, and when the former has descended to its final position, as at F ^{50} , dotted lines, Fig. 7, the blank has been completely folded and the sides b b' are between the adjacent faces of 105 the former and the side plates D D, and the end followers B B are then moved up to give the final setting or pressure to the end sections b ^{3} and the bottom and stay sections b ^{4} b ^{2} . When this occurs, the only portions of 110 the box above the throat are the cover-flaps b ^{5} b ^{6} and the small rectangular flaps b ^{20} at the tops of the end sections b ^{3} , the lips m and m' 115 being so located that after they have performed their requisite functions they will not interfere in any way with the final folding and completion of the box. The former-shaft F' has its vertical reciprocation 120 imparted thereto in a substantially well-known manner by means of a link f ^{20} , connected with a rocker-arm f ^{21} , fast on a rock-shaft F ^{2} , mounted on a part of the arch Q and rocked by suitable and usual means, the link f ^{20} 125 being pivoted to a bracket F ^{3} , secured to the shaft F'.

Referring to Fig. 5, the former is made hollow and the shaft F' is tubular, having bearings f ^{22} and f ^{23} for the shudder-rod O, the bearing f ^{22} being part of a coupling f ^{24} , which connects a dash-pot chamber f ^{25} with the upper end of the former-shaft F', said chamber at its upper end having an opening f ^{26} , the

size of which is regulated by a valve f^{27} . A coiled spring s^{10} surrounds the shedder-rod between the top of the bearing f^{28} and a collar f^{28} , secured to the rod and having a locking-lug f^{29} extended laterally through a longitudinal slot f^{30} in the shaft F' , the spring normally acting to maintain the shedder retracted, as in Fig. 5, the shedder-rod having at its upper end a piston f^{31} , movable in the dash-pot chamber.

A bracket F^4 (shown separately in Fig. 2^c) is rigidly secured to the top of the arch or head Q and has ears f^{40} , extended on each side of the shaft F' , and a lever f^{41} , bifurcated at its inner end at f^{42} , is fulcrumed between the ears on a pin f^{43} , the bifurcated ends of said lever being slotted at f^{44} , Fig. 5, to receive a pin f^{45} , extended into vertical slots f^{46} in the sides of bracket F^4 . This pin f^{45} has mounted upon it a latch f^{47} , having a depending leg carrying a roll f^{48} , held by a spring s^{12} against or in position to engage the beveled end of a pin f^{49} , adjustably secured in upright position on bracket F^3 by a set-screw 100. The lever f^{41} is connected by a link f^{50} with a short arm f^{51} on the rock-shaft F^2 , so that when the latter is turned to depress the former F the link will act to rock the lever, lifting the pin f^{45} to the upper ends of the slots f^{46} and elevating the latch f^{47} , while at the same time the beveled pin f^{49} descends, so that the spring s^{12} operates to swing the latch toward the shaft F' in position to snap over and hold the locking-lug f^{29} when it is brought into coöperation with the latch about the time the former F is at its lowest point.

The relative position of former and shedder-rod O has not yet been changed from that shown in Fig. 5; but after the box has been formed and the former begins to rise the latch f^{47} will prevent rise of the shedder-rod and its foot o^x will engage the bottom of the box and hold it from moving up with the former, while at the same time the spring s^{10} will be compressed. As the shaft F' rises the lever f^{41} will gradually return to its normal position, (shown in Fig. 2;) but the spring s^{12} will still hold the latch operative with its roll f^{48} in the path of the cam-rod f^{49} , which is rising with the shaft F' , and when the beveled end of said rod engages the roll it will swing the latch on its fulcrum f^{45} , withdrawing it from the lug f^{29} , and thereby releasing the shedder-rod. The latter is then lifted by expansion of the spring s^{10} to its normal position relative to the former-shaft F' and the former; but the sudden expansion of the spring is prevented by the dash-pot, so that all shock or jar is prevented, the shedder-rod resuming its normal retracted position gradually and at a speed determined by the adjustment of the valve f^{27} . The release of the shedder is not effected until after the former F has been withdrawn entirely from the box, and the latter drops out of the folding-throat

as soon as the members B B and D D thereof separate in readiness to coöperate with the next blank.

It now remains to describe the blank-supporting means onto which the blanks are delivered with a sliding movement by the blank-conveyer and the means for accurately positioning each blank upon the supporting means in readiness to be acted upon by the box-forming mechanism. The blank-supporting means consist of tracks K , located in parallelism outside of the end followers B B and supported on transverse rods K^X , mounted in the arch Q , said tracks supporting the longitudinal edges of the blank and in this instance the outer longitudinal edges of the side sections b^3 of the blank, lateral movement of the blank being prevented by the upright sides k of the tracks. These sides are provided with overhanging guards k' at the ends nearer the blank-pile, the free ends of the guards being preferably upturned, as shown in Fig. 4, the guards preventing the leading portion of the blank from flying up as the conveyer-rods h carry the blank forward and slide it along the tracks K .

A back-stop E^{10} , shown as a strip of metal secured to the bed Q^X of the frame, Figs. 3 and 4, is arranged to accurately position the back transverse edge of the blank when the former F' descends, the upper horizontal portion of the back-stop having raised lips or shoulders e^{10} for the purpose of engaging the blank midway between its sides. Considerable momentum is imparted to the blank by the blank-conveyer as it slides the blank onto and along the tracks K , and it has been found that if a fixed stop is provided to limit the feed movement of the blank the latter will sometimes hit the stop with sufficient force to cause it to rebound somewhat, and the resulting inaccurate position of the blank will cause an imperfect box to be made. To overcome this objection, I have provided a stop, which normally is beyond the position desired for the coöperating transverse edge of the blank, means being provided to move the stop in a retrograde direction to a predetermined point after the blank has been deposited by the blank-conveyer. This final position of the stop is such as to position the blank with absolute accuracy, and the initial position of the blank is such that the maximum momentum of a blank can only carry it up to the stop, and ordinarily the blank may not quite reach the stop. Then on the retrograde movement of the latter, which preferably is slow, the blank will be moved more or less oppositely to its feed movement into the precise position requisite to perfect action thereupon by the box-forming mechanism, the back-stop referred to preventing any accidental rearward movement of the blank beyond proper position. So far as I am aware this mode of effecting the final positioning

of the blank is broadly new, and I have shown herein one means for practically effecting the same.

Referring to Figs. 3 and 4, the end followers B B have mounted on their outer faces slides v , held in place by screws v' , passed through longitudinal slots v^2 in the slides, and to the outer left-hand end of each slide is secured an upturned stop v^x , which projects into the path of the leading edge of the blank. A rod v^3 connects the slides v and projects at each side beyond them to loosely enter forked arms v^4 , fast on a rock-shaft v^5 , mounted in bearings V on the main frame of the machine, the ends of the rods being thus slidable in the arms v^4 when the end followers B B are moved in and out. The rock-shaft has a rocker-arm v^{5x} , to which is pivotally connected a link v^6 , forked at its upper end at v^7 , Fig. 2^b, to embrace the rock-shaft F², which operates the former F, said rock-shaft having secured to it a collar v^8 , provided with a wing v^9 , in which a cam-groove v^{10} is formed to receive a roller or other stud v^{12} on the link v^6 .

In Fig. 2 the blank-conveyer is shown as having just delivered a blank to the blank-supporting means described and just about to return for the next blank to be fed and the stops v^x are stationary in the path of the leading edge of the blank, a similar condition of affairs being shown in Figs. 3 and 4. Now the former descends, due to turning of the rock-shaft F², and as the latter turns the wing v^9 moves in the direction of arrow 102, Fig. 2^b, the cam-groove v^{10} acting on the stud v^{12} to lift the link v^6 slowly, and thereby to move the slides v by the connections described to the right, Figs. 3 and 4. The slow inward movement of the stops v^x thus produced causes them to act upon the blank and move it from the position shown in Figs. 3 and 4 to the right just far enough to place the blank in absolutely correct position, and the former F descends upon it and the folding begins. Reverse movement of the wing v^9 restores the stops to their normal position in readiness for the next blank as the former returns to its uppermost position, so that the stops are ready to prevent any possible overrunning of the blank. The tracks K are slightly higher than the tops of the conveyer-rod, so that when they return they cannot carry the blank backward, the leading edge of the blank riding up over the back-stop E¹⁰ on its feeding movement and thence onto the tracks as the abutment-hooks h⁷ continue the feed movement of the blank. The distance between the back-stop shoulders e¹⁰ and the final inward position of the stops v^x is equal to the extreme distance between the leading and rear edges of the blank. When at rest, the side lifter m² rests on the rod v^3 between the stop carriers or slides v , as shown in Figs. 3 and 4.

Various changes or modifications may be

made in different details of construction and arrangement of the several novel features of my invention without departing from the spirit and scope thereof, as I have shown and described herein one practical embodiment of my invention.

Having described my invention, what I claim as new, and desire to secure by Letters Patent, is—

1. In a paper-box machine, a blank-pile support, upright, longitudinally-notched gages to position the blank-pile at the leading corners thereof, a gummer-picker to gum and lift the topmost blank of the pile, and a flat, separator-blade located between the gages to act upon the blanks between their leading corners and separate the next blank from the topmost blank when the latter is lifted.

2. In a paper-box machine, a support for a pile of slitted blanks superposed one upon another, a gummer-picker to gum and lift the topmost blank of the pile, and a fixed thin and flat separator-blade to enter the slits of the blanks and by frictional engagement with the opposite edges of the slit thereof overcome lifting of the second blank due to suction between it and the topmost blank.

3. In a paper-box machine, a support for a pile of slitted blanks superposed one upon another, a gummer-picker to gum and lift the topmost blank of the pile, and a plurality of upright, thin and flat parallel blades to enter the slits of the blanks and by frictional engagement with the opposed slitted edges prevent lifting of a plurality of blanks simultaneously by the operation of the gummer-picker.

4. In a paper-box machine, box-forming mechanism, means to support the blank to be acted upon thereby, a blank-conveyer to convey a blank to said supporting means, and independent movable means to engage the blank and effect its accurate positioning relative to the forming mechanism.

5. In a paper-box machine, box-forming mechanism, means to support the blank to be acted upon thereby, a blank-conveyer to convey blanks one by one to said supporting means, and means movable oppositely to the feed movement of a blank, to engage the leading end of and move a blank into position to be acted upon by the box-forming mechanism.

6. In a paper-box machine, box-forming mechanism, means to support the blank to be acted upon thereby, a blank-conveyer to convey a blank to said supporting means, and means intermittently movable oppositely to feed movement of the blank to engage the leading end of the blank and accurately position it upon the supporting means.

7. In a paper-box machine, box-forming mechanism, means to support the blank to be acted upon thereby, a blank-conveyer to convey a blank to said supporting means, a device in the path of movement of the blank,

to stop its forward movement due to the action of the conveyer, and means to thereafter move said device oppositely to feed movement of the blank, and accurately position the latter relatively to the forming mechanism.

8. In a paper-box machine, box-forming mechanism, a reciprocating blank-conveyer to convey a blank to said mechanism, a positioning device to engage the conveyed blank and by retrograde movement thereof accurately position it relatively to said forming mechanism, and means to intermittently actuate said positioning device.

9. In a paper-box machine, box-forming mechanism, blank-supporting means, a horizontally-reciprocating conveyer to convey a blank to said means, a device in the path of movement of and to permit the blank to move beyond its proper position relative to the box-forming mechanism, and means to thereafter impart a slow movement to said device oppositely to the feed movement of the blank, to engage the latter and effect its accurate positioning relative to the box-forming mechanism.

10. In a paper-box machine, box-forming mechanism, blank-supporting means, a conveyer to engage and slide a blank longitudinally upon said means, a device in the path of the leading end of the blank, and means to move said device to accurately position the blank after the same has been slid upon the supporting means.

11. In a paper-box machine, box-forming mechanism, blank-supporting means, a reciprocating conveyer to engage and slide a blank longitudinally upon said means, intermittently-operative means to thereafter accurately effect the positioning of the blank relative to the box-forming mechanism, and a fixed back-stop to limit retrograde movement of the blank.

12. In a machine for making paper boxes from blanks of the character substantially as specified, the combination with box-forming mechanism, of blank-supporting means, a horizontally-reciprocating blank-conveyer to convey a blank to and slide it upon said means, stops in the path of a transverse leading edge of the blank, said stops being beyond the proper position for such edge when the blank is slid upon the supporting means, and means to thereafter move the stops oppositely to the feed movement of the blank, to engage the leading edge thereof and accurately position the blank relatively to the box-forming mechanism.

13. In a paper-box machine, a blank-conveyer comprising parallel, horizontally-reciprocating rods, abutments adjustably mounted thereon, to engage the blank, a cross-bar, means to reciprocate it, and annularly-grooved rolls mounted in pairs on the rods and adapted to engage opposite sides of the cross-bar, to connect the latter and the rods and permit free movement of the latter toward and from each other, the grooves of

the rolls preventing disengagement of the rods and cross-bar.

14. In a machine of the class described, box-forming mechanism, a blank-support, comprising parallel, stationary tracks above the box-forming mechanism to receive and support a blank; means to adjust the tracks toward and from each other; a blank-conveyer to convey a blank to the blank-support, and independent means to accurately position the blank upon the blank-support.

15. In a machine of the class described, a folding-throat, stationary tracks to support the blank at its sides above the throat, overhanging guards at the inlet ends of the tracks, a back-stop for the blank, and means movable oppositely to feed movement of the blank to engage the latter and effect its accurate positioning on the tracks subsequent to the delivery of the blanks thereupon by the conveyer.

16. In a paper-box machine, box-forming mechanism comprising a vertically-reciprocating former and a coöperating folding-throat; parallel tracks to engage the longitudinal edges of and support a blank over the folding-throat; overhanging guards at the inlet ends of the tracks, to prevent lifting of the blank; a horizontally-reciprocating blank-conveyer to engage a blank and slide it beneath the guards upon the tracks, the latter being higher than the top of the blank-conveyer, and means to lift the leading edge of the blank being fed to the level of the tracks.

17. In a paper-box machine, box-forming mechanism comprising a vertically-reciprocating former and a coöperating folding-throat; parallel tracks to engage the longitudinal edges of and support a blank over the folding-throat; overhanging guards at the inlet ends of the tracks, to prevent lifting of the blank; a horizontally-reciprocating blank-conveyer to engage a blank and slide it beneath the guards upon the tracks, the latter being higher than the top of the blank-conveyer, means to lift the leading edge of the blank being fed to the level of the tracks, a back-stop for the rear edge of and to prevent retrograde movement of a blank, and means to engage the blank after it has been deposited on the tracks, and to move it back against the back-stop.

18. In a paper-box machine, a horizontally-reciprocating blank-conveyer, a vertically-reciprocating former, a coöperating folding-throat comprising end followers and upstanding side plates, blank-supporting tracks fixedly mounted outside of and parallel to the end followers, the tracks being higher than the level of the blank-conveyer, means to lift the leading end of the blank being fed to the track-level, a back-stop for the blank, and means operative after deposit of the blank upon the tracks to accurately position such blank relatively to the folding-throat and former.

19. In a paper-box machine, a former, a co-

operating folding-throat comprising approaching and receding side-folding plates, and end followers, and independently-operating means to engage and lift the side portions of the blank, operating in conjunction with the folding-throat, said means including pairs of elongated, pivotally-mounted fingers, and mechanism independent of the former to swing said fingers positively.

20. In a machine for making paper boxes from blanks of the character substantially as specified, the combination with a vertically-reciprocating former, of a coöperating folding-throat comprising end followers, and approaching and receding, upstanding side-folding plates; a separately-actuated side-lifter to act upon the under surface of one side section of the blank and swing it up against a vertical face of the former, and means actuated independently of but operating in conjunction with the side-folding plates to engage near their edges, and lift the side sections of the blank.

21. In a paper-box machine, the combination with the vertically-reciprocating former, and the movable members constituting the contractible folding-throat beneath the former, of independently-actuated means to engage and lift the side sections of a blank contemporaneously with the descent of the former and the contraction of the folding-throat.

22. In a paper-box machine, the combination with the vertically-reciprocating former, and the movable members constituting the contractible folding-throat beneath the former, of pairs of elongated fingers mounted to swing in vertical planes and adapted to engage the under surfaces of and lift the side sections of the box at the beginning of the folding operation, and means to actuate the fingers independently of the throat-forming members, the fingers preventing bending down of the supported portions of the blank as the former and throat-forming members coöperate.

23. In a paper-box machine, the combination with the vertically-reciprocating former, and the movable members constituting the contractible folding-throat beneath the former, a device to engage one of the side sections of the blank midway between its sides, means actuated by or through descent of the former to swing said device upward and thereby lift the portion of the blank sustained thereby, and independently-actuated pairs of swinging fingers to engage and lift one side section and the two end sections of the blank at the beginning of the folding of the blank by co-operation of the former and the throat-forming members.

24. In a paper-box machine, a vertically-reciprocating former, a coöperating contractible folding-throat comprising movable end followers and approaching and receding side-folding plates arranged in opposite pairs, a

side-lifter fulcrumed between one pair of said plates and having a cam end in the path of the former, said lifter being swung upward by the action of the former upon its cam end, 70 to lift the overlying side section of the blank, and independent swinging fingers operated by or through inward movement of the side plates to engage and lift both the side sections of the blank preparatory to complete 75 coöperation of the former and folding-throat.

25. In a machine for making boxes from blanks having side sections and end sections on one of the side sections, a former, a contractible folding-throat, means to engage the 80 side sections and swing them upward at the commencement of the folding operation, and means to engage and lift the end sections at such time, said means being separate from and operating independently of the means 85 for lifting the side section to which the end sections are attached.

26. In a paper-box machine, the combination with the reciprocating former, a contractible folding-throat with which it coöperates, 90 and means to support the blank in position to be operated thereby, of means, including pivotally-mounted elongated fingers located at opposite sides of the former-path to engage and swing the side sections of the blank 95 upward from the horizontal as the former begins to depress the bottom section of the blank into the folding-throat, connections between and to move the fingers on their fulcras in unison in opposite directions, and means 100 independent of the former to positively swing the fingers.

27. In a machine for making boxes from blanks having end-forming sections and side-forming sections, a reciprocating former, a 105 contractible folding-throat coöoperating therewith, means operating independently of the folding-throat to lift the side-forming sections as the former enters the folding-throat, and separate means to simultaneously engage 110 and lift the end-forming sections.

28. In a machine for making boxes from blanks having long side sections, and end-forming sections on one of the side sections, the combination with a blank-support, a contractible folding-throat beneath the supported blank, and a vertically-reciprocating former above and to enter said throat, of upwardly-swinging and independently-actuated devices to extend beneath and lift the side sections, 115 means to similarly coöperate with and lift the end-forming sections, said means being operatively connected with one of the upwardly-swinging devices, and separate mechanism to operate said swinging devices as the former 120 descends upon the blank and begins to depress the latter into the folding-throat.

29. In a paper-box machine, a gummer-picker to gum and lift the topmost blank from a pile of blanks, box-forming mechanism, a 130 blank-conveyer to engage the lifted blank and convey the same to the box-forming mechan-

ism, and automatic means to thereafter effect the accurate positioning of the blank relative to the box-forming mechanism.

30. In a paper-box machine, a gummer-
5 picker to gum and lift the topmost blank from a pile of blanks, box-forming mechanism, a blank-conveyer to engage the lifted blank and convey the same to the box-forming mechanism, and intermittently movable means to
10 stop the feed movement of the blank delivered by the blank-conveyer and thereafter to automatically effect the accurate positioning of the blank relative to the box-forming mechanism.

15 31. In a paper-box-making machine, box-forming mechanism, including a reciprocating former, a blank-conveyer to convey blanks singly to said mechanism, means to engage and position the blank when delivered by the
20 conveyer, and actuating connections between said means and the former, to accurately position the blank simultaneously with the descent of the former.

32. In a paper-box-making machine, box-forming mechanism, including a reciprocating former, a blank-conveyer to convey blanks singly to said mechanism, intermittently movable means to effect the accurate positioning of the blank relatively to the box-forming mechanism, and actuating connections between the former and said means, to operate the latter and position the blank as the former is about to engage it.

33. In a paper-box machine, a vertically-reciprocating former, means, including a rock-shaft, to actuate it, a cam on said rock-shaft, a folding-throat below and to coöperate with the former, a conveyer to feed blanks one by one between the former and the folding-throat, a stop in the path of and to limit feed movement of the blank, and connections between the cam and stop, to move the latter and position the blank accurately immediately before the descent of the former upon
45 the blank.

34. In a paper-box machine, a vertically-reciprocating former, a coöperating contractible folding-throat comprising end followers and side-folding plates, a blank-conveyer, stop-carriers slidably mounted on the end followers and having upturned stops in the path of the leading edge of the blank, and means to slide the stop-carriers simultaneously opposite to feed movement of the blank, to accurately position the latter relative to the folding-throat and former.

35. In a paper-box machine, a vertically-reciprocating former, a coöperating contractible folding-throat comprising end followers and side-folding plates, a blank-conveyer, stop-carriers slidably mounted on the end followers and having upturned stops in the path of the leading edge of the blank, and means actuated by the movement of the former to
60 move the stop-carriers opposite to feed movement of the blank as the former descends, to position the blank, and to return said stop-

carriers and their stops to normal position as the former rises.

36. In a paper-box machine, box-forming mechanism, including a former, a shedder working therethrough, means to effect downward movement of the shedder in unison with the former, a device to hold the shedder down and stationary when the former rises, to thereby shed the box, and means to release the shedder thereafter from the control of the retaining device.

37. In a paper-box machine, a former, a tubular, vertically-reciprocating shaft to actuate it, a shedder working longitudinally in said former and its shaft, means to effect downward movement of the shedder and former in unison, and means to hold the shedder down and stationary temporarily when the former rises, to thereby shed the box from the former.

38. In a paper-box machine, box-forming mechanism, including a former, a shedder working therethrough, a spring to lift the shedder, means to hold the shedder down and stationary when the former rises, to thereby shed the box from the former, and a device to thereafter automatically release the shedder and permit the spring to lift it into normal position relative to the former.

39. In a paper-box machine, box-forming mechanism, including a former, a shedder working therethrough, a retracting-spring for the shedder, means to temporarily hold the shedder down and stationary as the former ascends, to strip the box therefrom, and to release the shedder at a predetermined rise of the former, and means to cushion the released shedder.

40. In a paper-box machine, box-forming mechanism, including a former, a shedder working therethrough, a retracting-spring for the shedder, means to temporarily hold the shedder down and stationary as the former ascends, to strip the box therefrom, and to release the shedder at a predetermined rise of the former, and a pneumatic cushioning device to control the spring-actuated retractile stroke of the shedder.

41. In a paper-box machine, a hollow, vertically-reciprocating shaft, a former attached thereto, a shedder working longitudinally in the shaft and former and having a laterally-projecting lug, a retracting-spring for the shedder, a latch to engage the lug when the former and shedder have descended to a predetermined point, to hold the shedder stationary when the former rises, and a device movable with the former to disengage the latch and lug, and thereby release the shedder, when the former has ascended a predetermined distance.

42. In a paper-box machine, a hollow, vertically-reciprocating shaft having a longitudinal slot, a lug on the shedder extended through said slot, a spring within the latter to lift the shedder and retract it, a latch to automatically engage said lug upon the de-

scent in unison of the former and shedder to a predetermined point, to hold the shedder down when the former ascends, compressing the spring, and means operated by ascent of the former to render said latch inoperative after the box has been shed, permitting the spring to expand and lift the shedder, retracting it to normal position.

43. In a paper-box machine, a hollow, vertically-reciprocating shaft having a longitudinal slot, a lug on the shedder extended through said slot, a spring within the latter to lift the shedder and retract it, a latch to automatically engage said lug upon the descent in unison of the former and shedder to a predetermined point, to hold the shedder down when the former ascends, compressing the spring, means operated by ascent of the former to release the shedder after it has shed the box from the former, permitting the spring to expand and retract the shedder, and an adjustable device to cushion the retractile movement of the shedder.

44. In a paper-box machine, a reciprocating former and a contained shedder movable

in unison therewith on the operating stroke thereof, means to temporarily hold the shedder stationary when the former moves back after operating, to strip the box from said former, and means to return the shedder 30 when released to normal, retracted position.

45. In a paper-box machine, a reciprocating former and a contained shedder movable in unison therewith on the operating stroke thereof, means to lock and hold the shedder stationary and thereby project it from the former on the return stroke thereof, to shed the box, an adjustable releasing device for and to unlock the shedder at a predetermined point on the return stroke of the former, and a spring to retract the shedder when released and restore it to normal position relatively to the former.

In testimony whereof I have signed my name to this specification in the presence of 45 two subscribing witnesses.
